(No Model.)

H. PHILLIPS & F. W. BYORS.
PICK OR TOOL HOLDER.

No. 417,502.

Patented Dec. 17, 1889.

UNITED STATES PATENT OFFICE.

HENRY PHILLIPS AND FRED W. BYORS, OF OTTUMWA, IOWA; SAID BYORS
ASSIGNOR TO SAID PHILLIPS.

PICK OR TOOL HOLDER.

SPECIFICATION forming part of Letters Patent No. 417,502, dated December 17, 1889.

Application filed February 2, 1889. Serial No. 298,520. (No model.)

To all whom it may concern:

Be it known that we, HENRY PHILLIPS and FRED W. BYORS, citizens of the United States, residing at Ottumwa, in the county of Wapello and State of Iowa, have invented certain new and useful Improvements in Pick or Tool Holders; and we do hereby declare the following to be a full, clear, and exact description of the invention, such as will enable others skilled in the art to which it appertains to make and use the same.

This invention relates to certain new and useful improvements in a holder for picks and similar tools; and it consists, substantially, in such features of construction and combinations of parts as will hereinafter be more particularly described or pointed out.

Miners and others meet with frequent losses of their picks or tools while being transported to and from the blacksmith-shop, and in all mines the miners have considerable trouble in sorting their picks from the piles into which it is a common practice to throw them after being sharpened.

The object of our invention is to provide a holder for picks which shall enable miners and others to keep their picks or tools together at all times when not in use, and by which the mistakes and losses of former occurrence are prevented, all as will hereinafter more fully appear when taken in connection with the accompanying drawings, in which—

Figure 1 represents in perspective a pick or tool holder constructed in accordance with our invention, the same indicating the manner in which the pick is placed and secured therein. Fig. 2 is a view in perspective of the three parts of which our holder is constructed, the same being intended to show each part as being formed from a single piece of metal. Figs. 3 and 4 represent side and perspective views, respectively, of modifications.

In carrying our invention into effect we form or construct the holder of three parts, two parts of which are hinged or linked together at one end, so as to permit the top part to be thrown back for the purpose of putting the picks in place, after which the top is closed and the three parts secured by a

suitable lock. For the purpose of preventing the picks being turned and extracted from the holder, we preferably provide a slide-stem, which also serves to strengthen the receiving portion of the holder and prevent distortion thereof. At intervals in the top portion of the holder we form a series of holes to receive the slide-stem, which is movable on the receiving portion for the purpose of adjusting the holder for the number of picks or tools placed therein.

Reference being had to the drawings by the letters marked thereon, A represents the bottom or receiving portion of our improved pick-holder, and B the upper or closing portion thereof. The lower part A is formed from a single piece of wrought-iron rod, the ends of which are welded together at a, and at which point a loop b is formed to receive in a hinge-like manner the shank c of the part B. At the other end of part A an eye d is formed for receiving the shackle of an ordinary padlock C, as shown in Fig. 1. Around part A a sliding loop D, with a division-stem E, is placed, which serves to make the divisions f—that is to say, by forming these changeable divisions and by moving said slide-stem along the holder longitudinally or lengthwise to adjust the holder for any number of tools, it will be seen that when a pick has been placed in and the parts locked together said pick cannot be turned around and withdrawn, as might be possible otherwise. The upper portion B is also constructed of a single piece of wrought bar-iron drawn down at g and forming the shank c, that is attached to the loop b, as shown. This part B is formed at its end opposite to c with an eye h, in which is held a link m, while at several points along its body are a series of holes n to receive the upper portion of the slide-stem E, for the purpose before stated. This construction is preferred on account of the manner in which the part of the pick-handle beyond the pick or blade is received and held from turning.

We do not limit ourselves as to size, but may construct the holders to receive as many tools as desired.

In the modification shown in Fig. 3 it will

be seen that when desired to make additional room in the holder the slide-stem can be moved along the part A and dropped to one side of eye d when divisions are not used.

15 It will also be seen in the modification, Fig. 4, that, if desired, the holder may be provided with one or more immovable or stationary stems to form divisions for the picks or tools. The adjustable stem, however, is preferred, 10 as and for the reasons stated.

When a number of picks are locked up and rested against a wall or other support, the top and bottom portions of the holder become reversed, as is obvious.

15 From the foregoing description it is thought the purpose and construction of our invention will be thoroughly understood; and we desire to say that we do not limit ourselves to the precise details of construction and arrangement shown, as immaterial departures therefrom could be made and come within the scope of our invention.

Having thus described our invention, what we claim as new, and desire to secure by Letters Patent, is—

25 1. In a pick-holder, the combination of the

part A, having its forward end fashioned into an eye, the part B, hinged at its rear end to the part A, and the link m, connected to the forward end of the part B and adapted to 30 pass over the eye, substantially as and for the purpose set forth.

2. A pick or tool holder constructed of the part A, formed with loop b and eye d, together with a slide-stem E, in combination with the 35 part B, formed with a series of holes, the shank c, and eye h, and having the link m fitted in said eye h, and a lock, substantially as described.

3. A pick or tool holder constructed of the 40 part A, having loop b and eye d, together with slide-stem E, and formed with the part B, containing a series of holes and hinged to said part A, and the link m, substantially as and for the purpose described. 45

In testimony whereof we affix our signatures in presence of two witnesses.

HENRY PHILLIPS.
FRED. W. BYORS.
